FIG. 5 is a rear elevation view thereof;

FIG. 6 is a top plan view thereof; and

FIG. 7 is bottom plan view thereof.

FIG. 8 is a front perspective view of a powder actuated tool showing my new design in accordance to a second embodiment;

FIG. 9 is a left side elevation view thereof;

FIG. 10 is a right side elevation view thereof;

FIG. 11 is a front elevation view thereof;

FIG. 12 is a rear elevation view thereof;

FIG. 13 is a top plan view thereof; and

FIG. 14 is bottom plan view thereof.

FIG. 15 is a front perspective view of a powder actuated tool showing my new design in accordance to a third embodiment;

FIG. 16 is a left side elevation view thereof;

FIG. 17 is a right side elevation view thereof;

FIG. 18 is a front elevation view thereof;

FIG. 19 is a rear elevation view thereof;

FIG. 20 is a top plan view thereof; and

FIG. 21 is bottom plan view thereof.

FIG. 22 is a front perspective view of a powder actuated tool showing my new design in accordance to a fourth embodiment;

FIG. 23 is a left side elevation view thereof;

FIG. 24 is a right side elevation view thereof;

FIG. 25 is a front elevation view thereof;

FIG. 26 is a rear elevation view thereof;
